UNITED STATES PATENT OFFICE.

MARC LANDRAUD, OF RENAGE, FRANCE.

APPARATUS FOR GUIDING FLEXIBLE BANDS OR BELTS IN MOTION.

Application filed May 11, 1926, Serial No. 108,358, and in France May 19, 1925.

My invention relates to an apparatus which is adapted to guide flexible bands such as belts, felt bands, or textile belts or bands passing over rollers, and to automatically return the said bands when deflected from their proper course.

The said apparatus comprises a main roller, which is mounted in a frame adapted to oscillate on a central pivot axle which is perpendicular to the axis of rotation of the roller. Upon the upper part of the said main roller are caused to bear two small rollers which are mounted on the said frame and are spaced apart by a distance which is very slightly in excess of the width of the band to be guided.

When the said band is deflected from its course, it will engage below one of the small rollers, and the pressure of said roller will cause the said frame and roller to pivot about in such manner that the band will be slightly displaced and will rapidly return to its original position.

A constructional form of the guiding apparatus according to my said invention is shown by way of example in the appended drawings.

Fig. 1 is an elevational view of the said apparatus with certain parts in section.

Fig. 2 is the corresponding plan view.

Fig. 3 is a side view on a larger scale, with certain parts in section.

In the said figures, the two end parts 4 and 5 which pertain to a stationary frame are connected together by an I-beam 6 which is placed flatwise, said I-beam comprising at the middle part a cup-shaped member 7 containing the vertical rollers 8 distributed around a central pivot axle 9 which is secured to an I-beam 10 resembling the beam 6 and disposed above the latter.

The beam 10 rests upon the beam 6 firstly by means of a circular row of balls 11 surrounding the axle 9 and secondly by means of two small rollers 12 mounted in the forked holders 13 disposed upon the beam 10 and bearing upon the roller races 14 secured to the beam 6 by a set of screws 15 for regulating the height.

The beam 6 carries at a suitable point a U-shaped member 16 (Fig. 3) whose branches are provided with adjustment screws 17 between which are disposed the beam 10. From this disposition it will result that the beam 10 may pivot in the cup 7 while still remaining horizontal, due to

the rollers 12, but its motion is limited at will by the stop-screws 17.

To the ends of the upper beam 10 are secured by the bolts 18 two right-angle brackets 19 which support in the bearings 20 the axles 21 of a roller 22, at a certain distance above the bearings 20, the brackets 19 are pierced with an aperture 23 traversed by a pivoted arm 24 whose thickness is less than the height of the aperture 23 and whereof the pivot axle 25 is maintained by the bracket 19 at the proper height by the plate 26 whose position before the said aperture can be vertically adjusted. As shown in Fig. 3 the position of the plate 26 is regulated by two screws 27 engaged in the bracket 19 and passing through the slots 28 in the said plate.

Upon the arm 24 is rotatably mounted between two collars 29 and 30 a roller 31 consisting of a suitable substance such as india rubber.

Above each arm 24 extends a support 32 which is secured to the angle bracket 19 by the nut 33 which is engaged in a slot 34 in the bracket. The ends of the arm 24 and of the support 32 are terminated by two small cups 35 mounted in opposite position, having between them the spring 36.

The adjustment of the respective heights of the arm 24 and the support 32 is such that the roller 31 will rest upon the upper part of the cylinder of the roller 32, and the least ascent of the said roller will greatly compress the spring 36.

The position of the roller 31 on the arm 24 is so regulated that the distance between the two rollers is very slightly in excess of the width of the band 37 passing over the roller 22.

The operation is as follows:
Let it be supposed that the band 37 moves slightly to the right in Fig. 1; it will then be engaged below the right hand roller 31 which will rise and compress the spring 36, thus exercising a great pressure on the main roller 22.

This pressure causes a frictional engagement between the bands and the corresponding end of the main roller thereby causing the same to move with the band 37; the main roller will thus rotate on the axle 9 until the beam 10 meets one of the abutments 17, and the left hand end of the said roller will be thus displaced in the direction contrary thereto.

The main roller being thus displaced in position, the band will move slightly to the left, and will be engaged below the left hand small roller 31; the opposite movement will now take place, and the band will return to the right.

After a certain number of diminishing oscillations, the main roller 22 will come into a position of equilibrium, and will leave this position only when outside interference again displaces the band to the right or left.

Obviously, the invention is not limited to the present example, and the apparatus is susceptible of numerous constructional modifications relating to the pivoting parts for the roller or to the supports for the lateral rollers.

I claim:

In a device of the character described, a base, a frame pivotally mounted thereupon, a main roller rotatably mounted in said frame, levers pivotally mounted in said frame above said main roller and extending inwardly over the ends thereof, rollers rotatably mounted on said levers and adapted to contact with said main roller at points near the ends thereof, arms extending inwardly from said frame above said levers and substantially the same length thereof, expansible springs positioned between the inner ends of said arms and the inner ends of said levers to maintain said rollers in contact with said main roller.

In witness whereof I have hereunto set my hand.

MARC LANDRAUD.
